No. 809,858.

PATENTED JAN. 9, 1906.

F. M. STRAUBE.

WRENCH.

APPLICATION FILED AUG. 11, 1905.

UNITED STATES PATENT OFFICE.

FRANCIS M. STRAUBE, OF BOULDER, COLORADO, ASSIGNOR OF ONE-HALF
TO LEWIS W. GODDARD, OF BOULDER, COLORADO.

WRENCH.

No. 809,858.

Specification of Letters Patent.

Patented Jan. 9, 1906.

Application filed August 11, 1905. Serial No. 273,749.

To all whom it may concern:

Be it known that I, FRANCIS MARION STRAUBE, residing at Boulder, in the county of Boulder and State of Colorado, have invented 5 certain new and useful Improvements in Wrenches, of which the following is a specification.

My invention relates to certain new and useful improvements in wrenches, and it relates 10 more particularly to that type of wrenches known as "monkey-wrenches" having sliding jaws.

The invention primarily has for its object to provide a wrench of this character of a very 15 simple and effective construction and in which means are provided for permitting an easy, rapid, and accurate adjustment of the sliding jaw and in which means are provided to hold the jaw in a firm position after it has been adjusted to the desired point.

Generically, my invention includes a wrench comprising a fixed jaw having a handle portion provided with a rack and a movable jaw 25 slidable on the handle portion of the fixed jaw and a pivoted arm secured to the movable jaw, which is provided with a thread and a collar, which nut has ring portions for entering the rack of the fixed-jaw handle and means 30 on the movable-jaw pivoted member for securing the same, with the collar, in engagement with the rack portions of the handle.

In its more detail nature my invention comprises certain novel construction, combination, and arrangement of parts, all of which 35 will be first described in detail and then specifically pointed out in the appended claims, reference being had to the accompanying drawings, in which—

Figure 1 is a perspective view of my invention, showing the movable jaw in position to be moved along the handle portion. Fig. 2 is a similar view showing the wrench as applied for use. Fig. 3 is a vertical longitudinal section of my invention. Fig. 4 is a horizontal section on the line 4 4 of Fig. 3. Fig. 5 is a 45 similar view on the line 5 5 of Fig. 3. Fig. 6 is a cross-section on the line 6 6 of Fig. 3. Fig. 7 is a detail perspective view of the pivoted arm and its jaw-engaging bearing member. Fig. 8 is a detail cross-sectional view 50 showing a slightly modified form of catch member. Fig. 9 is a similar view of a modified form of pivoted arm and its jaw and arm member separated.

Referring now to the accompanying drawings, in which like characters of reference indicate like parts in all of the figures, 1 designates the fixed jaw, which has an integrally-formed handle 2 and a nut-engaging face 2^x, as shown. The handle 2 is provided on one edge face 2^y with a rack portion 2^a, as shown. Longitudinally slidable on the handle 2 is a jaw 3, which comprises the body portion 3^a and the yoke or strap portion 3^b, which surrounds or embraces the handle 2 and which, together with the body portion 3^a, forms an elongated guideway for the handle 2, as shown. The body portion 3^a and the yoke or strap portion 3^b may be made integral, if desired, or the same may be made in separate parts, as shown in the drawings, and secured together by rivets or otherwise. At the upper front end the sliding jaw is cut away to form a recess 3^c and to provide ears 3^d 3^d, which ears 3^d 3^d are apertured to receive the rivet 4, which secures the pivoted arm 5 to the jaw. The jaw 3 is formed with a shoulder 3^e in the recess 3^c to coöperate with a shoulder 5^e on the head 5^a of the arm 5, which arm 5 comprises the head 5^a, having a portion to enter between the ears 3^d 3^d of the jaw 3 and apertured, as at 5^b, to permit passage of the rivet 4. The shoulder 5^e of the head 5^a is adapted to abut the shoulder 3^e of the jaw 3 when the parts are in the position shown in Fig. 2. 85

The head 5^a may be provided with a threaded portion 5^d to receive the threaded arm proper, 5^e, which arm 5^e is screwed into the threaded portion 5^d and may be further secured thereto by a pin 5^f in the aperture, if desired, as shown in Fig. 9, or the head 5^a and arm 5^e may be integral, as shown in Fig. 1.

The threaded arm 5^e receives a collar 6, which is provided with an internal annular aperture 6^a to coöperate with the threaded arm 5^e and which is provided with external annular rings 6^b 6^b, which enter the rack portion 2^a of the handle 2 at times to hold the jaw 3 in place.

At its free end the arm 5 has a non-threaded portion 5^g, forming a shoulder with the reduced portion 5^h of the arm 5^e.

7 designates a lock-pawl having an aperture 7^a to fit on the extending end 5^h of the arm 5^e, where it is pivotally held by the ring 7^c, which ring in turn is held from coming off by upsetting the end of the portion 5^b, as at 5^s, as clearly shown in Fig. 9, or the pawl

may be held in place by the portion 5^g, as shown in Fig. 1. The pawl 7 is substantially U-shaped in longitudinal section to embrace the handle 2, and the said pawl terminates in the finger end 7^b, which locks over the edge 2^c of the handle 2 when the collar 6 has its rings 6^b in engagement with the rack portion 2^a of the handle 2, and the said pawl 7 thus locks the arm 5 in the position shown in Fig. 2.

10 In Fig. 8 I have shown a slightly-modified form of pawl or latch member, by reference to which it will be seen that the pawl 7 in this form has its finger end 7^b slightly extended and provided with an undercut portion 7^c, in 15 which a locking-spring 7^d is secured, and the said spring 7^d rides in a longitudinal groove 2^e in the edge 2^c of the handle 2 when the parts are in the position shown in Fig. 2, so as to insure the pawl always remaining in its 20 secured position when once adjusted.

8 designates a stop portion on the handle 2 for limiting the movement of the sliding jaw 3.

So far as described the manner in which my invention operates will be best explained as 25 follows: The operator first moves the arm 5 to the position shown in Fig. 1 to release the collar 6 from engagement with the rack 2^a and then moves the sliding jaw 3^a against the nut until the spaces between the nut-engaging 30 faces 2^x and 3^x of the jaws 2 and 3, respectively, are the proper distance apart. The operator then moves the arm 5 to the position shown in Fig. 2 and secures it in such position by the pawl 7. Should the adjustment 35 of the jaws be too loose, it is only necessary to turn the collar 6, when the jaws may be moved closer together or farther apart, as desired.

I am aware that sliding-jaw wrenches have 40 heretofore been provided in which a pivoted member carrying a worm-gear is secured to the sliding jaw for meshing with a rack portion of the handle; but my invention differentiates from such construction in that the 45 collar 6 is not a worm-gear and has no gear function whatever with the rack portion of the handle, the collar and rack portion of the handle merely serving as a locking means to hold the jaw from longitudinal motion when 50 once set and serving to adjust the jaw by turning the collar on the arm with which it has a threaded engagement.

The handle 2 is recessed, as at 2^m, and provided with a spring 2ⁿ to coöperate with the 55 arm 5^e to hold the latch 7 tight.

From the foregoing description, taken in connection with the accompanying drawings, it is thought the complete construction, operation, and many advantages of my invention will be readily understood by those skilled in the art to which it appertains, and I desire to say that slight changes in the detailed arrangement of parts may be made without departing from the invention or the scope of 65 the appended claims.

Having thus described my invention, what I claim, and desire to secure by Letters Patent, is—

1. A wrench comprising the combination with a fixed jaw and a handle having a rack-face, of a sliding jaw longitudinally movable on said handle, a threaded arm secured to said sliding jaw, an internally-threaded collar on said threaded arm, said collar having external rings for coöperating with the rack portion of the handle, means at the free end of the arm for locking the same with the handle and a spring device carried by the handle for engaging the free end of the arm to force it away from the handle, substantially as shown and 75 described.

2. A wrench of the character stated, comprising the combination with the fixed jaw and a handle having a rack portion, of a movable jaw longitudinally slidable on said handle, an arm pivotally secured to said slidable jaw, said arm comprising a head portion and a threaded shank, an internally-threaded collar on said threaded shank, said collar having external rings for coöperating with the rack 90 portion of the handle, a U-shaped locking-pawl pivotally secured to the said threaded shank at its free end and adapted to lock over said handle and spring devices carried by the handle for engaging the arm to force it away 95 from the handle, substantially as shown and described.

3. A wrench of the character stated, comprising the combination with the fixed jaw and a handle having a rack portion, of a movable jaw longitudinally slidable on said handle, an arm pivotally secured to said slidable jaw, said arm comprising a head portion and a threaded shank, an internally-threaded collar on said threaded shank, said collar having 105 external rings for coöperating with the rack portion of the handle, a U-shaped locking-pawl pivotally secured to the said threaded shank at its free end and adapted to lock over the said handle, said portion having a finger 110 end, and a locking-spring secured to said pawl in said finger end for locking with said handle, substantially as shown and described.

4. A wrench of the class described, comprising the combination with a fixed jaw and 115 a handle integrally secured thereto, of a movable jaw longitudinally slidable on said handle, an arm pivotally secured to the sliding jaw, said arm and said sliding jaw having co-operating shoulders, a collar longitudinally 120 adjustable on said arm, said collar having external rings for coöperating with the rack portion of the handle, a locking-pawl pivotally secured to the free end of said arm for locking with said handle, and a spring device 125 carried by the handle for engaging the free end of the arm to force it away from the handle, substantially as shown and described.

5. A wrench comprising the combination with a fixed jaw and a handle having a rack- 130

face and a grooved portion, of a sliding jaw longitudinally movable on said handle, and a threaded arm pivotally secured to said sliding jaw, an internally-threaded collar on said threaded arm, said collar having external rings for coöoperating with the rack portions of the handle, means at the free end of the arm for locking the same with the handle, said free end of the arm adapted to rest in the grooved

portion of the handle and a spring in the grooved portion of the handle for engaging the free end of the arm to force it away from the handle substantially as shown and described.

FRANCIS M. STRAUBE.
